SELF ADJUSTABLE RAMP

Jerome W. Baer, Miami Beach, Fla.

Application October 27, 1958, Serial No. 53,175

Term of patent 14 years

(Cl. D15—8)

Fig. 1 is a perspective view of a self adjustable ramp showing my new design in one position of use; and

Fig. 2 is a similar view looking from the opposite side and showing my new design in another position of use.

The characteristic features of my design reside in the portions shown in full lines.

I claim:

The ornamental design for a self adjustable ramp, as shown and described.
